FOREIGN PATENT DOCUMENTS

HK 1802238-0003 * 11/2018

Primary Examiner — Paula Allen Greene

(57) **CLAIM**

The ornamental design for an earphone, as shown and described.

DESCRIPTION

FIG. 1 is a front perspective view of a first embodiment of an earphone showing our new design;
FIG. 2 is a back perspective view of the first embodiment;
FIG. 3 is a front view of the first embodiment;
FIG. 4 is a back view of the first embodiment;
FIG. 5 is a top view of the first embodiment;
FIG. 6 is a bottom side view of the first embodiment;
FIG. 7 is a right side view of the first embodiment;
FIG. 8 is a left side view of the first embodiment;
FIG. 9 is a front perspective view of a second embodiment of an earphone showing our new design;
FIG. 10 is a back perspective view of the second embodiment;
FIG. 11 is a front view of the second embodiment;
FIG. 12 is a back view of the second embodiment;
FIG. 13 is a top view of the second embodiment;
FIG. 14 is a bottom view of the second embodiment;
FIG. 15 is a right side view of the second embodiment; and,
FIG. 16 is a left side view of the second embodiment.
